COMBINED PAPER CONVERTING AND
INSERTING MACHINE

Andreas A. Bourdes and William Yiakoumelos,
Chicago, Ill., assignors to Narrownap Folding
Machine Company, Chicago, Ill., a common-
law trust

Application June 8, 1932, Serial No. 616,136

5 Claims. (Cl. 270—9)

Our invention relates to a combined paper converting and inserting machine, and has for its principal object the provision of an improved construction of this character which will be highly efficient in use and economical in manufacture.

The paper converting mechanism of our combined paper converting and inserting machine is substantially similar to that disclosed in United States Patent No. 1,719,833, dated July 9, 1929.

Our present invention has for one of its many objects a simple and inexpensive arrangement for inserting within the folds of a folded article, such as, for example, a paper napkin, towel, or the like, a strip of paper having printed thereon certain advertisement whereby when the articles are withdrawn from a dispenser and unfolded, the said strip of paper bearing the advertisement will be brought to the attention of the person unfolding the article.

In connection with paper napkins, principally the type of napkin mechanically folded by means of paper converting machines such as described in the patent herein referred to, the napkins are generally displayed upon the tables or counters of restaurants in appropriate holders from which they are dispensed by the user. By confining a printed slip or elongated strip of paper in the folds of these napkins a simple and inexpensive means of advertising is accomplished. It is, therefore, another object of this invention to provide a machine which will print an advertisement upon a moving paper web and cut said web into strips of predetermined lengths to be folded with napkins produced by the converting mechanism of our improved machine.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary vertical sectional detail view of a machine embodying our invention;

Fig. 2 is a sectional detail view of the same taken substantially on line 2—2 of Fig. 1;

Fig. 3 is a fragmentary sectional detail view taken substantially on line 3—3 of Fig. 2;

Fig. 4 is a fragmentary sectional detail view of the same taken substantially on line 4—4 of Fig. 1;

Fig. 5 is a fragmentary sectional detail view taken substantially on line 5—5 of Fig. 4;

Fig. 6 is a fragmentary sectional detail view taken substantially on line 6—6 of Fig. 5;

Fig. 7 is a fragmentary sectional detail view taken substantially on line 7—7 of Fig. 5; and

Fig. 8 is a diagrammatical perspective view of the folding mechanism embodied in the invention.

Fig. 9 is a perspective view of one of the products of the machine.

While we have illustrated in the drawings a specific paper converting machine, it is to be understood that the machine illustrated is the preferred form of construction. However, the paper converting machine may vary in construction and design to produce napkins and towels or like articles such as are now commercially in use.

We will first describe the folding mechanism of our combined paper converting and inserting machine. The machine illustrated in the drawings, as hereinbefore mentioned, is substantially similar to that described in the aforesaid patent.

In this connection the folding block or head is indicated at 10, and this block is supported in any suitable manner from the frame 11 of the machine. At the lower end portion of this block 10 or head, preferably the inverted apex thereof, are arranged creasing and feeding rollers 12 and 13, the roller 13 being supported by means of a bracket 14. The roller 12 is supported by means of bearing blocks 15 slidably supported in any suitable manner by means of the bracket 14, and these blocks 15 are adjustable so as to vary the distance between the rollers 12 and 13 by means of adjusting screws 16. This adjustment assures positive feeding of the web to the next folding means.

The paper web is paid from a jumble roll (not shown), and as paid from this roll the paper is passed over the folding block or head 10 and then projected through the creasing and feeding rollers 12 and 13. From these rollers 12 and 13 the paper web 17 is passed over a second folding block or head 18 which is supported from a rod 19 in turn supported by a bar 20 from the frame 11. This folding block or head 18 gives the folded paper web a second longitudinal fold, and from this block or head 18 the folded web passes between creasing and feeding rollers 21 rotatably supported from the frame 11 as at 22.

From these folding and creasing rollers 21 the paper web is again folded longitudinally by passing the folded web over a third folding block or head 23 supported from a rod 24 in turn supported from the frame 11 as at 25. From this folding block or head 23 the folded web is passed

between feeding and creasing rollers 26 and 27, the roller 27 being supported in any suitable manner by means of a bracket 28, whereas the roller 26 is adjustably supported by blocks 29 which blocks are slidably mounted upon the brackets 28 and adjusted relative thereto by adjusting screws 31.

From these creasing and feeding rollers the paper web, now having been folded into a plurality of coinciding longitudinal folds, is passed through a pair of cutting rollers 32, one of which cutting rollers includes a groove 33 adapted to co-operate with the cutting blade 34 to cut the folded paper web into strips of predetermined lengths.

Co-operating with one of the cutting rollers is a folding roller 35 having a groove 36 formed therein for the reception of the cutting blade 34, and this roller 35 co-operates with the adjacent roller 34' of the cutting rollers 33 for folding the paper web after the same is cut into a strip of predetermined length, transversely upon itself when said strip is fed between the rollers 34' and 35 by means of a feed bar 37 which is supported for reciprocation by means of a suitable bearing block 38 preferably formed as a part of the frame 11. The strip after having been given its final transverse fold is delivered from the roller 35 by means of a suitable delivery roller 39 upon which the strip is passed as it leaves the roller 35.

The operation and construction of the converting machine as described is substantially the same as that set forth in the patent herein mentioned, and for a more detailed description of the construction and operation of the converting machine reference may be had to said patent.

The inserting mechanism preferably includes a bracket structure 40 supported from the frame as shown in Fig. 1. Depending from this bracket structure 40 are spaced arms 41, which arms support a bar 42 in turn supporting a roll of paper 43. The bracket 40 rotatably supports a printing roller 44 designed to print certain matter upon the paper web as the paper web passes this roller in a manner to be hereinafter described. The ink is fed to the printing roller by means of feed rollers 45 which feed rollers pick the ink from an ink trough 46 supported by the bracket 40.

The web 43' from the paper roll 43 passes between the printing roller 44 and a roller 47. From these rollers the paper web is passed over rollers 48 and 49 supported by arms 50 carried by the frame 11. From the roller 49 the web 43' passes downwardly between feeding rollers 51, which feeding rollers are rotatably supported by means of plates 52 supported from the frame 11 in a suitable manner.

From the rollers 51 the web 43' passes through a suitable guiding structure 53 which comprises a pair of spaced plates 54 and 55, which guide the paper through the cutting rollers 56 and 57, the roller 57 carrying the cutting blade 58 and the roller 56 being provided with the cutting groove 59. These cutting rollers 56 and 57 cut the web 43' into predetermined lengths, and these lengths pass through a guiding structure 60 similar to the guiding structure 53. From this guiding structure 60 the cut strips are delivered for passage between the cutting rollers 32, so that the strip will be disposed in parallel relation with the longitudinal folds of the web 17.

To assure delivery of the cut strip as cut from the web 43' a feeding mechanism is provided.

This feeding mechanism includes a pair of spaced arms 62 and 62' provided with rings 63 mounted upon eccentric discs 64 fixed upon a shaft 65. Carried by the arms 62 and 62' is a pin 61' on which is mounted a knurled roller 61 adapted to have contact with the knurled surface of the adjacent roller of the feed rollers 32 through a slot 64' formed in an extension 65' of the guiding structure 60, Fig. 5. The arm 62' is positioned in a recess 66' formed in this extension, whereby to prevent rotation of the arms yet to allow proper longitudinal movement thereof by action of the eccentric discs 64. The arrangement is such that the roller 61 by action of the eccentric discs 64 is brought into contact with the strips 15 and during that contact this roller with the co-operation of the rotating roller 32 will deliver the severed strip from the web 43' at the proper time so that when the feeding blade 37 operates upon the folded web 17, the strip from the web 20 43' will be folded with the severed strip of the web 17 in the manner shown in Fig. 8 of the drawings. The cutting rollers 56 and 57 as well as the shaft 65 are operatively connected by sprocket and chain connections 66 so that these 25 elements will be timed for proper operation whereby to deliver the severed strip from the web 43' to a position to be folded with the longitudinal folded web 17 when the same is projected between the roller 35 and the adjacent roller of 30 the cutting rollers 32, which is the final fold given to the article converted by the machine.

While we have illustrated and described the preferred form of construction for carrying our invention into effect, this is capable of variation 35 and modification without departing from the spirit of the invention. We, therefore, do not wish to be limited to the precise details of construction set forth, but desire to avail ourselves of such variations and modifications as come 40 within the scope of the appended claims.

Having thus described our invention, what we claim as new and desire to protect by Letters Patent is:

1. A device of the type described comprising 45 means for making longitudinal folds in a web of paper, means for cutting a second web into lengths, means for delivering said strips successively to a position adjacent the folded web, means for cutting said folded web into napkin 50 units after said strips have been delivered to a position adjacent the folded web, and means for folding the napkin units over said strips.

2. A device of the type described comprising 55 means for making longitudinal folds in a web of paper, means for cutting a second web into strips of predetermined lengths, means for delivering said strips successively to a position adjacent the folded web, means for cutting said folded web into napkin units after said strips have been delivered to a position adjacent the folded web, and means for folding said napkin units over the strips.

3. In a device of the type described, a pair of 65 pinch rollers having means for severing a web of paper passing therebetween into napkin units, a second pair of pinch rollers having means for severing a second web of paper into strips of predetermined length, means for guiding said strips 70 into a position adjacent said first-named web, to pass therewith through said first-named pair of pinch rollers, and means arranged in operative relation with said first-named pair of pinch rollers to fold said napkin units over said strips 75.

as they pass in pairs from said first-named pinch rollers.

4. In a device of the type described, a pair of pinch rollers for receiving a web of paper, said rollers being provided with cutting means for severing the web into pieces of predetermined length, a second pair of pinch rollers for severing a second web into strips of predetermined length, means for guiding said strips into operative relation with said first-named web, to pass with the latter through said first-named pinch rollers, said means comprising in part an eccentrically operated pressure member, and means for folding said pieces and said strips in assembled relation as they pass from said first-named pinch rollers.

5. In a device of the type described, means for making longitudinal folds in a web of paper, a pair of pinching rollers for receiving said web of paper, said rollers being provided with cutting means for severing the folded web into napkin units, a second pair of pinch rollers for severing a second web of paper into strips of predetermined length, means for guiding said strips into juxtaposed relation with the folded web of paper, to pass with the latter through said first- 10 named pinch rollers, and means for folding the napkin units upon said strips. 5
